AUTOMATIC ASSEMBLING MACHINE

Curtis D. Speer, Warren, Pa., assignor to Sylvania Electric Products, Inc., a corporation of Massachusetts

Application November 19, 1947, Serial No. 786,932

12 Claims. (Cl. 218—0.5)

1

This invention relates to part-handling mechanisms for assembling machines and to automatic assembly machines embodying such mechanisms. The invention is addressed particularly to the automatic assembly and staking of tubular terminals to a molded shell to form a tube-base for radio tubes and like devices, and to the handling of parts in such operations.

Partly automatic base-staking machines are known having automatic mechanisms for loading tubular pins into fixtures, requiring an attendant to apply a molded, apertured shell to each fixture previously loaded with pins, and having cyclically operated mechanism for staking each set of pins into the shell. An object of the present invention is to adapt such a machine more fully to automatic operation by providing a transfer mechanism for feeding and applying the preformed shells to the pins previously inserted in the fixtures.

Where an automatic feeder for shells is used it is important to prevent the machine from staking an incomplete set of pins into a shell to form a tube-base, for such tube-base would be defective. Where an attendant is present it is comparatively simple to guard against missing pins, as will occur in the event of mechanical failure in the pin feeder. With an automatic shell feeder and inspector would be required to sort out the defective products and considerable waste would be entailed. Accordingly, another object of this invention is to devise a sequence of operations to the end that the waste of parts and defective products may be avoided. In accomplishing this purpose, I test for the presence of a full complement of pins in each fixture after pin-loading but before shell-loading. The result of this test is used to control the subsequent shell-applying operation. In this connection a further object of the invention is to provide a shell-transfer device in combination with a pin tester and subject to control thereby. The presence or absence of a shell is subsequently relied on for removal of pins from the fixture before it reaches the pin-staking tools. No shell is wasted where the set of pins is incomplete, and incomplete sets of pins are recovered. Furthermore, there is assurance that the bases produced are complete.

The pins conventionally are shouldered below the shell. The preferred form of pin ejector which I have devised includes a cyclically operable pneumatic pin-extractor, being rendered ineffectual by the presence of the shell itself wherever a shell has been loaded. With no mechanical connection of the ejector to either the

2

tester or the shell loader I have thus enabled selective removal of pins, preventing waste of pins incidental to failure of the pin-feeder without disturbing the normal sequence of operations.

Further objects of the invention and novel features will be apparent from the following detailed disclosure of a specific illustrative embodiment thereof. In the drawings which show the specific illustrative embodiment of the present invention,

Figs. 1 and 2 are plan and elevation views respectively of the entire machine, emphasizing the novel shell-transfer unit and its location in relation to the other operative stations;

Fig. 3 is an elevation, partly in section, of the pin-testing unit and its associated electrical circuit;

Fig. 4 is a perspective view of the form of shell to which the illustrated machine is particularly adapted;

Fig. 5 is a perspective view of a single base-staking fixture, two pins being shown therein;

Fig. 6 is a sectional view of the fixture, with the shell seated on the pins;

Fig. 7 is an elevation of the pin unloader, the pin stakers, and the remover for the completed bases;

Fig. 8 is an enlarged fragmentary sectional view of a completed base showing a single staked pin; and

Fig. 9 is a detail view of certain portions of the shell-transfer unit.

Fig. 10 is a side view of the indexing mechanism employed by the invention.

A brief description of the machine and the mechanisms utilized at the successive stations follows, showing the nature of the mechanisms and how they work to produce the desired results.

The automatic base staker illustrative of the present invention is shown in plan and elevation views in Figs. 1 and 2 respectively. Turret 12 is supported on stationary ring 13 carried by bed plate 10 to carry tube bases fixtures 14 stepwise in counterclockwise rotation past a series of operative stations. Barrel cam 15, carried by continuously rotating shaft 20 located beneath base plate 10, projects upward through the base plate to a zone adjacent the under surface of turret 12, where its cam track 16 engages a series of cam followers 18 secured to the underface of turret 12. Drive shaft 20 makes one revolution for each machine cycle to index the turret one step.

At the start of a processing cycle fixtures 14

approach pin loader 22 having multiple flexible tubular guides 24, one for each pin to be loaded into each fixture. Pins P are fed, one set at a time, to tubes 24 and are dropped into apertures or ports 19 of fixtures 14 (Fig. 5). Tube-base fixtures 14 are then carried successively past tester 26 for automatically checking for a full complement of pins P in fixture 14; to base loader 28 where shells S (Fig. 4) are applied to the tops of pins P in fixture 14 (Fig. 6); to automatic pin ejector 30 for removing inadvertently incomplete sets of pins P; past stakers 32 and 34 where the top ends of the pins P are spread and staked against the inside of shells S (Fig. 8); and finally to ejector station 36 for removing the completed tube-bases.

Where a single pin of a set is lacking in any fixture 14 as determined by tester unit 26, operation of shell-applying unit 28 is later suppressed under control of unit 26; and unit 30 is effective thereafter to remove all pins from any fixture 14 where shell-applying was suppressed. The sequence of operations involving the suppression of shell-applying and the subsequent removal of the incomplete complement of pins prevents stakers 32 and 34 from jamming pins in fixtures 14.

The following portion of the specification describes in detail the structure and operation of each of the cooperating work station units.

The construction and operation of pin-loader 22 is well known in the art. Its details form no part of the present invention. It normally operates to deliver a complete set of pins or inserts to each fixture 14, one pin being dropped down each tube 24 in each machine cycle.

The nature of the shell-feeding and applying unit will be appreciated from Figs. 1, 2, 6 and 9. Preformed parts, bodies, or shells S are supplied by inclined chute 38, where they are carried with depending central locators L. The locator is provided with a rib R that orients (as will be seen later) the shell properly with respect to fixtures 14 and insures the proper relation of the pins to that rib (where the base being assembled does not employ the maximum number of pins as is frequently the case with bases for vacuum tubes).

The shells are pulled by gravity, one at a time, into the peripheral recesses, sockets, or pockets 40 of feed plate 42 and are carried counterclockwise toward the loading position which is reached in two steps of feed plate 42. Chute 38 incorporates supporting flanges 44 and 46. A supporting and guiding plate 48 is extended arcuately about feed plate 42 from the lower end of flange 44 and acts to support and confine the shells during transit. Workpiece shells S are delivered to arm 50 which is resiliently pressed by spring 52 to grip one shell in cooperation with feed plate 42, at the level established by plate 48.

Shells S are individually transferred to successive fixtures 14 by a rotary and axially reciprocable plunger 54 (Figs. 1, 2 and 6) having a peripheral groove 56 in its bottom end for receiving pins P. Rotary plunger 54 is carried in bearing 58 for sustained rotary drive by pulley 60, belt 62, pulley 64, and by motor 66 through internal reduction gearing. Bearing 58 is vertically reciprocated along stationary pin 70 by rod 68, actuated by lever 72, cam follower 74 and cam 76 on drive shaft 20. Cam 76 times the reciprocation to occur when a shell S is to be applied to a fixture 14 directly in line with plunger 54, and in which pins P previously have been loaded. Descent of bearing 58 under this control causes plunger 54 to pass into shell S obtaining light 75

frictional engagement with its walls and pressing downward on its bottom, to force shell S out of the grip of resilient arm 50 and feed plate 42 toward the fixture 14 until rib R contacts said fixture. During this descent, as at other times, plunger 54 is maintained in rotation. The rotary motion thus transmitted is effective to turn shell S until rib R on locator L is aligned with complementary recess 18 of fixture 14 (Fig. 5) whereupon the plunger drops and forces the shell onto the fixture and pins and the locator descends into the central aperture of the fixture. Engagement between rib R and recess 18 stops the shell from rotating despite frictional contact with rotating plunger 54. The plunger 54 is preferably made of rubber or other soft resilient material so that efficient driving contact may be established with the shell until locator L drops into recess 18. Lever 72 then elevates plunger 54, and turret 12 advances another fixture 14 into position below the plunger. Simultaneously feed plate 42 is indexed one step during the one-step advance of turret 12, another shell S being then advanced to arm 50. By this means shell S is properly oriented so that its pin-receiving apertures receive the pins already in place in fixture 14.

Feed plate 42 (see Fig. 2) obtains its rotary drive from shaft 84 through the slip drive provided by friction plates 80 bearing against the lower face of ratchet 94, the drive to the friction plates 80 being provided by sprocket 82 which is rotatably mounted on shaft 84 and urged upward by coil spring 86. Sprocket 82 is partly encircled by drive chain 88, which is in turn driven by sprocket 90 on shaft 91 of turret 12 and therefore receives the indexing motion of the turntable. In order to limit the motion of feed plate 42, it is latched against rotation by pawl 92 and ratchet 94 pinned to shaft 84. This pawl is withdrawn and restored at the proper times by cam follower 98 and cam 96 on shaft 20, the cam and cam follower being maintained in engagement by spring 100.

Shell-transfer from arm 50 to fixture 14 is suppressed under control of disc 102 on shaft 104 when the fixture at the transfer station has in it less than the desired number of pins. Disc 102 has four normally vertical interponents 106. Shaft 104 is rotated by sprocket 108 which is engaged by chain 88 driven by turret 12. Interponents 106 can be shifted to incline outwardly by electromagnet 110 and bell crank 112 under control of the pin-checking unit 26, as will be seen. As illustrated there are two feed steps of turret 12 between pin-checking unit 26 and plunger 54 of transfer unit 28. There are, correspondingly, two steps of control disc 102 between the setting position of the interponent 106 adjacent electromagnet 110 and the position of that interponent when adjacent shaft 68. It will be self-evident that plunger 54 will be maintained in the elevated position shown, despite its release by lever 72 and control cam 76, when a shifted interponent is carried below shaft 68. This suppression occurs only when electromagnet 110 was energized to shift that interponent 106 adjacent thereto when, two steps earlier in the rotation of the disc 12, checking unit 26 energized electromagnet 110. After passing shaft 68, the interponents 106 are carried past a stationary plate (not shown) above the level of their pivots which restores the sloping interponents to their normal vertical position.

Electromagnet 110 of the shell transfer sup-

pressing mechanism is energized under control of pin-checking unit 26 (best seen in Figs. 2 and 3). This unit comprises a head 118 which is cyclically lowered into contact with the pins in each fixture 14 by means of lever 114 secured to shaft 116, the shaft being oscillated in turn by the same lever 12 that lowers the shell-applying head. Head 118 of the checking unit is secured to vertically reciprocable shaft 120 the lower end of which has a collar 124 secured thereto and a coil spring 122 for urging collar 124 against lever 114. Head 118 is penetrated by stationary vertical shaft 126 that guards head 118 against swinging about the center of shaft 120, thereby maintaining that head directly above each fixture 14 as it is arrested at this station.

Testing head 118 includes plural testing pins 128 of insulating material that are slidable in block 130 of brass or other electrically conductive material. To each pin there is secured a metal collar 132, pressed against block 130 by compression spring 134 which reacts against conductive plate 136. It is apparent that an electrical circuit will be completed between terminal 135 in block 130 and terminal 137 in plate 136 by any collar 132 and its spring 134 so long as any pin 128 remains in its lowered position. All of the testing pins in head 118 are lowered when the head is in the elevated position shown, and, if any pin P is lacking, the corresponding testing pin will remain lowered after head 118 descends. Where less than the full complement of pins is to be employed the testing pins which correspond to purposely omitted pins P may be disabled as by blocking them in an elevated position.

Electromagnet 110 of the shell transfer suppressing mechanism is in series with the internal connections in elevated head 118, but is not normally energized because of interposed, normally open-circuit switch 138 located in a position beneath and in the line of travel of lever arm 114. This switch is closed only when head 118 reaches its lower limit; and at such times terminals 135 and 137 will be bridged only where one or more pins P is lacking in fixture 14.

Normally, where there is a complete complement of pins P in fixture 14, the circuit between terminals 135 and 137 of head 118 will be broken just before switch 138 is closed, and magnet 110 will not be energized. But, where a pin P is lacking, electromagnet 110 will be energized as head 118 is fully lowered, thus shifting the upper end of the interponent 106 adjacent thereto away from shaft 104. Thus when that fixture 14 which has been found to carry an incomplete complement of pins P is indexed two steps forward into position under plunger 54, the shifted interponent 106 will have been rotated into position beneath shaft 68 where it is enabled to suppress the shell supplying stroke of plunger 54. When any interponent 106 is thus effective to suppress the shell-applying operation, the shell S which was to have been delivered to the fixture 14 remains gripped between arm 50 and feed plate 42. Sprocket 82 at this time due to the grip of finger 50 on the non-transferred shell, is ineffectual to force rotation of the feed plate because of the slip between friction plates 80.

Fixtures 14 are advanced stepwise toward units 30, 32, 34 and 36, the working tools of which are carried by vertical slide 140. This is reciprocated in alternation with the indexing operations of the turret by drive shaft 20 through a cam-operated linkage not shown. Pin-removal unit 30 (Figs. 1 and 7) comprises a block 141, hollowed

out-to-fit down over and to enclose the circle of pins P in fixtures 14, the hollow being extended as a tubular exit-chute 142. Also secured to the reciprocable portion of unit 30 is a valve-control arm 144. A normally closed air valve 146 is supported by bed plate 10 adjacent the path of arm 144, to be opened thereby once every stroke of slide 140. An air supply line 148 is connected to delivery line 150 when valve 146 is opened. Base 10 supporting ring 13 is hollowed to provide cavity 152 below block 141 and is connected to air line 150. Fixtures 14 have through-passages 154 which are continuations of the pin apertures 19 in fixtures 14. When slide 140 descends, if there is no shell S on the fixture 14 below block 141, the block 141 rides all the way down and is brought to bear on the fixture while valve 146 is simultaneously opened. The compressed air, delivered through air line 150, then expels all of the pins of the incomplete set of pins in the fixture, the pins passing out through exit tube 142.

The dotted lines indicate the lowered position of block 141, in the instance where shell-applying previously had been suppressed under control of unit 26 due to the absence of sufficient pins in a fixture 14. Block 141 is carried by squared rod 156 in slide bearing 158. Where there is a shell S on any fixture underlying block 141, the descent of slide 140 will merely permit block 141 to press the shell downwardly against the enlargement in the pins whereby the shell will prevent pin-removal when valve 146 is opened by the operation of arm 144, bearing 158 descending along rod 156.

Shells S and full complements of pins P are carried by fixtures 14 beyond unit 30 without effect. Staking heads 32 and 34, carried on slide 140 with a relatively stiff internal spring mounting (not shown), are then effective to spread the upper ends of tubular pins against the insides of shells S as shown in Fig. 8. The staking tools are ineffectual with respect to bared fixtures 14 as they pass readily into the pin-less apertures. Were there, of course, an incomplete set of pins left in any fixture 14, those pins would be jammed in the fixture in the absence of a shell S.

At the next work station, the completed tube bases are raised from fixtures 14 by arms 160 of unit 36, the arms being resiliently pressed toward each other so as to slip over and latch below the completed bases. An air jet (not shown) is effective to eject the bases laterally from arms 160.

A brief description of the operation of the invention described above follows: Intermittent rotation of the turret 12 is caused by the action of barrel cam 15 on the depending cam followers 18, the barrel cam 15 being continuously rotated by drive shaft 20. As the turret 12 is rotated, its radially spaced fixtures 14 are carried beneath the work stations comprising pin loader 22, tester 26, shell loader 28, automatic pin remover 30, stakers 32, and 34, and ejector station 36, in sequence. At these stations the various assembly steps necessary to the production of a completed base assembly are accomplished, namely: the loading of pins into the fixture, the checking of the loaded fixture for the proper number and location of pins, the loading of shells to the fixtures and onto the tops of the pins where a proper complement of pins has been found, the removal of pins from those fixtures to which the shell loader has not loaded shells due to the absence of a proper complement of pins, the staking of pins to the shells which constitutes the final step

of assembly and, lastly, the removal of the completed base from the fixture.

At pin feeder 22 the desired number of pins are fed to the proper, predetermined orifices in the successively stationed fixtures 14 by means of the delivery tubes 24 in a manner already known in the art.

Fixture 14 is then indexed around to tester 26 where a check is made by the contacting portions of vertically reciprocating head 118 for the proper complement of pins in given fixture 14. The head 118 is lowered under the influence of timed cam control from power shaft 20, and descends through a suitable linkage onto each fixture 14 as it stops at that station. If a pin is lacking from a desired pin recess in fixture 14, contacts within head 118 remain closed, and, when the descending under portion of head positioning lever 114 strikes micro switch 138, an electrical circuit is completed which operates on solenoid 110 at the shell supplying station to cause suppression of the shell supplying operation when the fixture which has been found deficient in its supply reaches that station.

In the event that a proper number of pins are found in the fixture, all of the contacts carried by head 118 are opened and no operating signal is sent to the suppressor portion of the shell delivery unit.

Fixture 14 then continues on its indexed circuit and, as shown in the drawings, arrives after two indexing steps at shell transfer unit 28.

Loading of the shell S onto the fixture is accomplished in two steps. The shells are supplied by inclined chute 38 with depending central locaters L and are set thereby into engagement with the recessed feed plate 42 which is stepped around simultaneously with turret 12 so as to supply an individual shell to a position above each fixture as it arrives at the loading station. When a fixture with the proper complement of pins stops beneath the shell, the continuously rotating plunger 54 is caused to travel downward into internal frictional engagement with the shell by downward travel of bearing 58 under control of a linkage operated by a cam on the continually rotating power shaft 20. Downward travel of plunger 54 and bearing 58 is continued to force the shell out of engagement with the feed plate 42 and spring loaded arm 50 into fixture 14 where the locator pin L of shell S eventually rotates into engagement with the slotted recess in fixture 14. The shell S then ceases to rotate and is forced downward into full engagement with the fixture by further travel of plunger 54 thereby receiving the upward protruding portions of the pins P in the holes provided. Plunger 54 is then drawn upwards and out of engagement with shell S, permitting the fixture to be indexed along towards the staking stations.

In the event that the proper number of pins has not been inserted in the fixture 14 by the pin feeding mechanism, a signal will have been transmitted from the pin sensing mechanism 26 to the suppressor solenoid 110. The latter operates to tilt an interponent 106 which is then transferred (by the rotation of disc 102 in steps corresponding to the position of the fixture found to contain the improper number of pins) into position beneath the vertical operating shaft 68, a part of the linkage controlling the lowering and raising of plunger 54 and bearing 58. The tilted interponent, when indexed into a position beneath rod 68, interferes with the downward travel of the assembly, thereby preventing delivery of

a shell to the defectively supplied fixture upon its arrival at the shell supply station. The operation of the mechanism at this station is thus to provide a shell to those fixtures only which arrive at the shell loading station with the proper complement of pins.

Fixture 14 is then indexed into position at the automatic pin ejector 30. Here, attached to a vertically reciprocating head 140 which also carries the staking tools 32 and 34 and an ejector mechanism 36 up and down simultaneously in timed relationship with the indexing of the turret, is the pin removal unit 30. At this station a blast of air released through valve 146 under control of arm 144 projecting from the vertical carriage of the pin ejector unit is applied to the fixture through a channel in the base plate beneath the fixture and under the ejector unit to the pin receiving apertures of the fixture. Although the air blast is applied to the fixture regardless of whether the proper number of pins are present in the fixture or not, the air blast is not effective to cause the removal of pins which are held in place by a shell, as would be the case where a proper number of pins were present. This is because the shell is held in place over the fixture and on the pins by pressure from block 141 which has moved downward under control of the main slide 140. Block 141 is yieldably linked to slide 140 so that its downward travel will be limited by the presence of a shell, or so that, in the absence of a shell, it may travel downward to a position immediately over and surrounding the fixture 14. In the latter case, the pins are not retained in place by the shell and are free to travel out of their apertures under the compulsion of the blast and upward into the guide recess in block 141, whence they are directed through a tubular delivery chute 142 to a suitable receptacle stationed adjacent to the turret on the frame of the machine. Upward travel of the ejector unit then terminates the air blast and permits indexing of the turret.

At succeeding machine stations 32 and 34, staking of the pins to the shell in fixtures 14 may be accomplished in a manner well known to the art. The staking tools are reciprocated in and out of work position by slide 140 as dictated by the indexing motions of the turret and are enabled by the absence of improperly assembled parts to stay free of jams.

The final assembly step occurs at the ejector station 36 where the completed base assembly comprising a number of pins P staked to shell S is removed from the fixture 14 by the clawed ejector tool 36 which is also vertically reciprocated by the slide 140.

The foregoing represents a specific embodiment of the invention, illustrating several of its novel aspects. It will be readily apparent that a wide range of substitution may be practiced within the spirit of the invention, and that the whole and the novel portions are adaptable to other uses. Such departure from the specific illustration is intended to be embraced in the appended claims.

What I claim is:

1. In a machine of the class described, a turret having a series of supports each adapted to receive a preformed body, means for holding one body at a time in axial alignment with each of said supports as they are successively advanced, and a reciprocable head for axially transferring said one body to said supports, said head including drive means for rotating said one body

during its axial approach toward said fixtures.

2. In a machine of the class described, a turret having a work-support carrying work orientation determining means, gripping devices for holding a workpiece in spaced opposition to said support, an axially reciprocable and rotatable member for transferring a workpiece from said gripping device to said work support and for rotating the workpiece in contact with said work orientation determining means and into proper orientation with respect thereto, and a rotary drive for said member.

3. In a machine of the class described, a turret having a work-supporting fixture, said fixture having a work-orientation determining portion complementary to a preformed portion of a workpiece, work-retaining devices opposite said fixture for frictionally sustaining a workpiece in spaced relation to said fixture, an axially reciprocable and rotatable transfer element opposite said fixture, and a rotary drive and a yieldable axial actuating mechanism for said transfer element, said drive and actuating mechanism being effective to cause transfer of the workpiece to said fixture and to rotate said workpiece with respect to said fixture into proper rotational orientation therewith.

4. In a machine of the class described, a work-supporting fixture, a peripherally pocketed feed plate for carrying workpieces individually over said fixture, an arm for pressing the workpiece against the pocket opposite said fixture so as to support the workpiece frictionally, and a work-applying head supported for vertical reciprocation through said feed plate pocket to said fixture.

5. In a machine of the class described, a work-supporting fixture, a peripherally pocketed feed plate for carrying workpieces individually opposite said fixture, an arm for pressing the workpiece against the pocket opposite said fixture so as to support the workpiece frictionally, a work-applying head supported for reciprocation along the transfer path from said feed plate to said fixture, and a yieldable rotary drive for said feed plate.

6. In a machine of the class described, a turret, a series of work-supporting fixtures carried by said turret, a feed plate and a stationary arm for delivering workpieces one at a time into spaced alignment over the fixtures successively advanced by said turret, a rotatable and vertically reciprocable plunger for transferring the workpieces to the fixtures successively and for frictionally rotating them during transfer to said fixtures, said fixtures having work-orienting means complementary to shaped portions of the workpieces.

7. A base-assembling machine comprising in combination, a series of work-supporting fixtures having a work-orienting portion and pin-receiving recesses, means for inserting pins into said recesses, a testing device to check the insertion of a full complement of pins in each of said fixtures, successively, a transfer unit for delivering shells individually to a position opposite said fixtures individually, said unit including a feed plate having a rotary frictional drive, an arm for frictionally confining a single shell in said position against said feed plate, a reciprocable and rotary plunger, a yieldable actuating mechanism for said plunger for transferring said workpieces individually toward said fixtures, and a rotary drive for said plunger effective during

its approach toward said fixtures for assuring proper orientation of the shell in relation to said fixtures, and a mechanism controlled by said testing device for suppressing the reciprocation of said plunger, thereby causing suppression of the rotation of said feed plate by the workpiece engaged by said arm.

8. In combination, a turret having at least one formed work-support and adapted to be rotated in a number of indexing steps to present said work support at a number of work stations, means for loading multiple inserts into said support, a testing device for checking the loading of all of said inserts, a transfer unit for applying a preformed part of the product to said support to overlie said inserts, said loading means, testing device and transfer unit being spaced peripherally about said turret, control means actuated by said testing device to determine the operation of the transfer unit so that no preformed part will be applied to said support where any insert is lacking, and a cyclically operable unit effective to remove all of the inserts from said support whenever operation of the transfer unit was suppressed.

9. In combination, a turret for supporting a series of fixtures, each of said fixtures having a series of ports adapted to receive an arbitrary number of inserts, a testing device for contacting the inserts in said fixtures, successively, to check for the presence of a full complement of inserts in said fixture supply means for workpieces, a transfer unit for applying workpieces over said inserts, and means under control of said testing unit for preventing operation of said transfer unit when a fixture having an incomplete complement of inserts arrives at said transfer unit, and a pneumatic ejector for clearing all those fixtures emerging from said workpiece-applying unit without superposed workpieces.

10. In combination, a turret having a series of work-supporting fixtures, a loader for inserting a full complement of pins into said fixtures, successively, a tester for thereafter checking the presence of a full complement of pins, a transfer unit for applying preformed bodies to said pins, said unit including a pocketed rotary feed plate, a stationary arm cooperating with the pocket of said feed plate in delivery position to maintain one body in spaced alignment with each of the fixtures on said turret as they are advanced successively, and a reciprocable and rotary transfer device, a pin remover coacting with said fixtures successively as they emerge from said transfer unit, the preformed bodies being effective to retain the pins in said fixtures so that the pins will be removed from only those fixtures lacking preformed bodies, and means for securing the pins to the bodies cyclically operable irrespective of the condition of loading of said fixtures.

11. A base-staking machine comprising a turret having a fixture carried thereby and apertured to receive terminal pins, said turret being adapted to be rotated in a number of steps to present said fixture successively to a number of work stations, a pin-loader, a shell-loader and a pin-staker at spaced peripheral points about said turret for assembling and staking base parts, and a pin-remover between said shell-loader and said staker for removing pins from said fixture whenever operation of the shell-loader is ineffective so that only those pins will be staked which are associated with shells.

11

12. A base-staking machine according to claim 11 wherein said pin-remover comprises a cyclically reciprocable head, a hollowed block slidably carried by said head and slidable in relation thereto and an air pressure supply cyclically controlled for applying pressure to the bottoms of the pins whereby only those pins will be removed that are not retained in the fixture by co-action of said hollowed block with a superposed shell.

CURTIS D. SPICER.
